(57) **CLAIM**

The ornamental design for a “swimming jig lure,” as shown and described.

DESCRIPTION

FIG. 1 is a front perspective view of the swimming jig lure, showing my new design;

FIG. 2 is a top plan thereof;

FIG. 3 is a bottom plan thereof;

FIG. 4 is a front elevation thereof;

FIG. 5 is a rear elevation thereof; and,

FIG. 6 is a left side elevation of the swimming jig lure illustrated in FIGS. 1-6, the opposite side being identical thereto;
